J. P. WRIGHT & C. A. CARLSON.
 PROCESS OF MAKING REINFORCED PAPER BOXES.
 APPLICATION FILED JUNE 26, 1917.

1,258,294.

Patented Mar. 5, 1918.

UNITED STATES PATENT OFFICE.

JACOB P. WRIGHT AND CARL A. CARLSON, OF BARBERTON, OHIO, ASSIGNEES TO THE DIAMOND MATCH COMPANY, OF CHICAGO, ILLINOIS, A CORPORATION OF ILLINOIS.

PROCESS OF MAKING REINFORCED PAPER BOXES.

1,258,294.

Specification of Letters Patent.

Patented Mar. 5, 1918.

Application filed June 26, 1917. Serial No. 176,940.

To all whom it may concern:

Be it known that we, JACOB P. WRIGHT and CARL A. CARLSON, both citizens of the United States, and both residents of Barberton, in the county of Summit and State of Ohio, have invented certain new and useful Improvements in Processes of Making Reinforced Paper Boxes, of which the following is a specification.

10 The object of this invention is to provide a simple, efficient and economical process of making rectangular paper or paste-board boxes having their walls reinforced and strengthened by inturned integral folds or 15 extensions of the material of which the bodies of the boxes are composed.

In carrying out the invention in the preferred way we provide a strip of box material equal in width, plus reinforcing side 20 flaps or folds, to ordinary box stock, which strip is drawn from a suitable roll and subjected to the progressive operations illustrated in the annexed drawings, wherein—

Figure 1 is a plan of a portion of a strip 25 of box-stock which has been subjected to glue-applying, scoring, punching and side-folding operations preparatory to the severance of a box-blank from the body of the strip.

30 Fig. 2 is a plan of the severed blank.

Figs. 3, 4, 5 and 6 illustrate successive conditions of the blank during the box-forming operation.

Fig. 7 represents the finished box.

35 The strip of box material A is drawn from a suitable roll in the direction indicated by the arrow. As the strip progresses it is supplied at predetermined intervals with surface lines or spots of glue, as at a,

40 It is then longitudinally scored on parallel lines b, c which respectively define the fold lines of the side walls of the box and of the reinforcing folds thereof. Longitudinal parallel slits, as d, are formed in the body 45 of the strip, at regular spaced intervals in the length of the strip, and substantially rectangular recesses, as at e, having their basal edges in spaced parallel relation to the slits are formed in the longitudinal edges

50 of the strip; the inner corners of the recesses being notched or incut parallel to the slits. Such slits, recesses and notches define the reinforcing laps f, corner tongues g, and end folds h for succeeding boxes. The

side laps, f, thus produced are folded inwardly upon and glued to the main side portions of the strip as indicated at i. The strip is then transversely scored on the lines j and k to provide fold lines for the end and corner portions of the box. The strip is then transversely severed midway between the ends of the succeeding side folds as on the line l, thus producing a box blank having two-ply side portions, end extensions h from the side folds, and end extensions m from the bottom, as shown in Fig. 2.

The two-ply side portions of the strip are then bent upward along the basal fold line b as indicated in Fig. 3, and each pair of end extensions h are then turned inwardly 70 on the fold lines k, at right angles to the upstanding sides, so as to overlap, as shown in Fig. 4. The tongues g being flexed by the inward folding of the end extensions reinforce the corners of the box. The bottom 75 extensions m are then turned upward on the fold lines k as indicated in Fig. 5. The upper portions, rising above the inturned extensions h, are then turned inwardly on the fold lines j, as seen in Fig. 6, and folded 80 down against the inner sides of the end extensions h and the corner tongues, as seen in Fig. 7. At the same time the inturned side and end folds are pressed hard against the adjacent surfaces of the structure so as 85 to insure the effective union of the contiguous parts.

We claim—

1. A process of making reinforced boxes which comprises forming in the body of a strip of box material, at spaced intervals in the length of the strip, pairs of longitudinal parallel slits; forming in the respective longitudinal edges of the said strip recesses having their basal edges in spaced parallel 90 relation to the slits, thereby providing pairs of side laps alternating with the pairs of slits; folding said laps upon and securing them to the adjacent portions of the strip; and severing the strip on transverse lines 95 medially of the slotted and recessed portions of the strip, thereby forming successive box blanks.

2. A process of making reinforced boxes which comprises forming in the body of a strip of box material, at spaced intervals in the length of the strip, pairs of longitudinal parallel slits; forming in the re-

spective longitudianl edges of the said strip recesses having their basal edges in spaced parallel relation to the slits and having their inner corners incut parallel to the slits, thereby providing pairs of side laps alternating with the pairs of slits and having end tongues; folding said laps and their tongues upon and securing them to the adjacent portions of the strip; and severing the strip on transverse lines medially of the slitted and recessed portions of the strip, thereby forming successive box blanks.

3. A process of making reinforced boxes which comprises forming in the body of a strip of box material, at spaced intervals in the length of the strip, pairs of longitudinal parallel slits; forming in the respective longitudinal edges of the said strip recesses having their basal edges in spaced parallel relation to the slits; thereby providing pairs of side laps alternating with the pairs of slits; folding said laps upon and securing them to the adjacent portions of the strip; severing the strip on transverse line medially of the slitted and recessed portions of the strip to form successive box blanks; and, finally, bending and uniting the lateral and

end portions of the blanks to provide boxes having reinforced sides and ends.

4. A process of making reinforced boxes which comprises forming in the body of a strip of box material, at spaced intervals in the length of the strip, pairs of longitudinal parallel slits; forming in the respective longitudinal edges of the said strip recesses having their basal edges in spaced parallel relation to the slits and having their inner corners incut parallel to the slits, thereby providing spaced pairs of side laps alternating with the pairs of slits and having end tongues; folding said laps and their tongues upon and securing them to the adjacent portions of the strip; severing the strip on transverse lines medially of the slitted and recessed portions of the strip to form successive box blanks; and, finally, bending and uniting the lateral and end portions of the blanks to provide boxes having reinforced sides, ends and corners.

Signed at Barberton, in the county of Summit and State of Ohio, this 23rd day of June, A. D. 1917.

JACOB P. WRIGHT.
CARL A. CARLSON.
